UNITED STATES PATENT OFFICE.

HENRY LIPKEMANN, OF NEW YORK, N. Y., ASSIGNOR, BY MESNE ASSIGNMENTS, TO THE ABCO BOILER CORPORATION, OF BROOKLYN, NEW YORK, A CORPORATION OF NEW YORK.

FURNACE.

Application filed October 25, 1923. Serial No. 670,743.

This invention relates to improvements in steam and water boilers known more generally as the round or house type.

The present invention contemplates the provision of means for supporting secondary combustion to the maximum degree over a wide area; to uniformly distribute air admitted for secondary combustion; to admit the air where the secondary combustion will play directly upon the boiler; to obtain the secondary combustion before the rising gases have been cooled; to incorporate the means for supplying the air into the furnace where it will not interfere with the general operation of the same, such as applying fresh fuel to the fire bed; to secure simplicity of construction and operation; and to obtain other advantages and results as may be brought out in the following description.

Referring to the accompanying drawings in which like numerals of reference indicate similar parts throughout the several views;

Figure 1 is a front elevation of a furnace, with the asbestos covering in sections so as to more clearly show the structure of the furnace;

Figure 2 is a sectional view upon lines 2-2 of Fig. 1 looking in an upwardly direction as indicated by the arrows:

Figures 3 and 4 are cross sectional views on lines 3-3 and 4-4 respectively of Fig. 2;

Figure 5 is a view similar to Figure 2, showing a modified structure; and

Figure 6 is a sectional view on line 6-6 of Figure 5.

In the specific embodiment of the invention illustrated in said drawings, the reference numeral 1 indicates the boiler or furnace in general which comprises a plurality of horizontal sections, the lower one of said sections as 2, constituting the ashpit, the next section 3 constituting the fire pot, sections 4 and 5 constituting the boiler or crown sheet sections for receiving water, and section 6 constituting the head or top section of the furnace. It is to be understood that the specific arrangement of these sections may be varied considerably, and in fact the number of sections may be altered, without departing from the scope of the present invention.

As is usual in the construction of such furnace, the boiler section 4 next above the

fire pot section 3 preferably constitutes a crown sheet 7 for the fire pot. The structure is such that section 4 constituting the crown sheet 7 overlies the entire upper opening of the fire pot and is of spider construction having a plurality of radiating slots 8 through which the gases from the fire bed may pass upwardly through the crown sheet to the next section and so on to the chimney.

In order to obtain secondary combustion, I provide a member 9 to immediately underlie crown sheet 7 and of the same spider form as the interior surface of said crown sheet. It will be observed in the present showing that the crown sheet is dome-like in shape, that is, the crown sheet goes up at its sides and then across like an inverted pan. The member 9 is slotted similarly to the crown sheet, that is, provides a plurality of radial slots 10 which register with the radial slots 8 with the crown sheet, so as to admit the rising gases from the fuel bed to pass through said slots 10 and 8. Preferably the member 9 is of suitable refractory material, such as fire-brick, so as to resist the heat and also to be strong enough to not be easily broken by coal thrown into the furnace. The structure described wherein the crown sheet is of dome shape is furthermore advantageous in protecting the member 9 against direct impact from coal thrown into the furnace in that it elevates said member somewhat out of the way.

The surface of the said member 9 is grooved, as at 11, next the crown sheet so as to provide in conjunction with said crown sheet a channel in which the air may pass. These grooves, indicated in Fig. 2, preferably provide a main channel and branch channels which open as indicated in Fig. 4 along the radial slots 10 and 8. The air passing through the main channel will therefore be free to pass out into the radial slots and combine with the uprising gases to form a secondary combustion which will operate directly upon the boiler or crown sheet surface to heat the water contained therein.

In order to admit air to the channels 11, I preferably provide a slot 12 between crown sheet section 4 and the fire pot section 3. At intervals, to register with said slots 12, I provide openings 13 connecting the slots 12 with channels 11. Air will accordingly enter free through slots 12 and 13 and channels

- 11 to the radial slots 9. It should be particularly observed that the arrangement set forth enables the rising gases to come in direct contact with the incoming air before the gases have reached any cooling surface and thus enable the necessary chemical combination to take place for the secondary combustion. It may also be noted that the outside slots 12 may be kept free from the usual asbestos covering 14 for furnaces by provision of outwardly directed flanges 15, 16 on the upper edge of the fire box section 3 and lower edge of crown sheet section 4 respectively.
- 13 Any suitable means desired may be employed for retaining the member 8 in position against the crown sheet. As illustrative of some such means, I have shown a stud or rivet 17 provided at the center of the said member and crown sheet, and have also shown a ledge around the upper edge of the fire pot section upon which the said member 8 will seat.
- 14 It is to be understood that I do not restrict myself to the provision of separate passages from the outside for each of the channels but may introduce the air through a limited number of channels to supply all. As illustrative of this structure, reference may be had to Figures 5 and 6 wherein reference numerals 19, 20 indicate the firepot section and crown sheet section respectively of a boiler. Crown sheet section 20 provides a crown sheet 21 having radiating slots 22 through which the gases from the fire bed may pass. Beneath the crown sheet is secured, as by central stud or rivet 23, a member 24 corresponding to member 9 heretofore described.
- 15 Said member 24 is provided with slots to register with slots 22 of the crown sheet and is provided on its upper surface with radial channels 25 between the said slots. These channels 25 all extend inwardly to a common central chamber 26, and one or more of the channels connect outwardly by an extension channel 27 with the atmosphere. Outside air may therefore enter through the extension channel 27 to the central chamber 26 and thus to the other channels 25 radiating therefrom. Obviously the air will have considerable opportunity to heat while passing through this course. A suitable shutter 28 may be provided at the outside of the furnace for opening or closing said extension channel as desired. Branch channels 29 are provided from the radiating channels which will permit the air to escape at the sides of the crown sheet slots as described in connection with the preceding structure.
- 16 Obviously detail changes and modifications may be made without departing from the spirit or scope of the invention, and I do not wish to be understood as limiting myself as to the exact structure shown as set forth in the following claims when construed in the light of the prior art.
- 17 Having thus described my invention, I claim:
1. In a furnace, the combination of a crown section provided with spaced radial draft openings, a member positioned on the under side of said crown member and in close proximity thereto having openings corresponding to the radial openings thereof, said last named member having grooves extending radially from the circumference toward the center thereof upon its upper surface and in communication with the exterior atmosphere, and laterally extending grooves upon said last named member connecting said radial openings with said radial extending grooves.
2. In a furnace the combination of a crown section of spider construction, the spaces between the legs of the spider constituting draft openings, a second spider member having corresponding openings, the legs of the second spider member formed with channels on their upper face, said channels extending radially and communicating with each other centrally and with the outside air circumferentially, and a plurality of transverse channels extending entirely across each leg and communicating with the radial channel therein, whereby when said second spider member is positioned against the under face of the crown section air admitted circumferentially to one of the said channels will be distributed through all of said channels and discharged against the lower edges of the legs of said crown section.
3. In testimony whereof I affix my signature.
- HENRY LIPKEMANN.
